AUTOMATIC HEIGHT GAUGE TAPPER

John F. McQuillan, Sr., East Orange, N. J.

Application May 7, 1942; Serial No. 442,109

3 Claims. (Cl. 33—189)

This invention relates to a layout punch and automatic height gauge tapper.

One important object of the invention is to provide a layout punch having a conical point whose center is exactly in line with the base of the punch holder.

Another object is to provide such a punch as will fit a vernier height gauge and will prick a mark in metal as accurately as a vernier height gauge can be set, preferably with the aid of a novel automatic height gauge tapper adapted to fit over the height gauge.

I further aim to provide the punch of such nature that it may be used as a scratch in the vernier height gauge.

Various additional objects and advantages will become apparent from a consideration of the description following taken in connection with accompanying drawings illustrating an operative embodiment.

In said drawings—

Figure 1 is a plan view of the height gauge tapper;

Figure 2 is an end elevation showing such height gauge tapper in connection with the punch, height gauge and work;

Figure 3 is a view taken approximately on the plane of line 3—3 of Figure 1 with a punch and work suggested;

Figure 4 is a plan view of the punch;

Figure 5 is an end elevation showing the punch used in connection with a supporting gauge and work;

Figure 6 is a view taken on the line 6—6 of Figure 5;

Figure 7 is an inverted plan view of the punch;

Figure 8 is a central longitudinal sectional view through a modified construction of the punch, and

Figure 9 is an elevation of a block or piece of work.

Referring specifically to the drawings wherein like reference characters designate like or similar parts, I provide a novel center punch having a body or stock 10 provided with a flat under surface 11. The stock 10 has a depending lug 12 provided, as shown in Figures 2, 3, 4, 5 and 7 with an integral punch element 15, or, as in Figure 8, with a hole or passage 13 which receives the shank 14 of a point or punch element 15'. It will be noted that such element 15 is truly conical and that its center is in the plane of the flat bottom wall 11. Stock 10 may have any desired number of openings 16 therethrough

to facilitate fastening it to a gauge, or other structure.

As shown in Figures 2 and 3, the center punch 10 is clamped to the slide 17 of a vernier height gauge 18 carried by a base 19 and which base is capable of sliding in all directions over its supporting surface. A yoke or clamp 20 is fastened to the slide 17 and the center punch passes through the latter being secured therein by a binding screw 21 carried by the clamp. The center gauge is shown in Figures 2 and 3 in operative relation to a metallic block or other work 22 maintained at the desired elevation by blocks 23, and clamped or fastened to a conventional backing 24 by means of a clamp 25. Such backing is shown of L-shape and in turn is secured to a support as by means of a clamp 26.

The punch 10 may serve as a scratch by moving the same or the vernier height gauge to 20 which it is attached in a horizontal plane. The block 22 may be shifted 90 degrees from the position shown in Figure 2 and the punch again used as a scratch, to intersect the scratch first made. Since the element 15 is truly conical, the scratches will be truly of V-shape. After the scratching, the point 15 will be located at the intersection of the scratches to receive a blow to give the necessary prick mark.

I employ an automatic gauge tapper which has an open frame or loop 27 which fits over the vernier height gauge as shown in Figures 2 and 3. This loop 27 at one end is spanned by a pin 28 on which a roller 29 is journaled and which roller may be placed in contact with the end of the center gauge 10. Loop 27 is detachably secured by a screw 30 to a stud 31 over the outer end of which a slidable head 32 is telescoped, being mounted and positioned by a screw 33 fastened to the stud 31 and passing through an elongated slot 34 on the head. Stud 31 and head 32 are normally held extended by an expansive coil spring 35 located in the hollows thereof. Head 32 may be slid inwardly into abutment with the outer end of the stud 31 and a hammer or other blow then dealt against the outer end of the head to slightly drive the center punch and produce the prick in the metal. Head 32 has a vent passage 36 leading from its hollow to the exterior.

It will be clear that the vernier height gauge is conventional and that the slide 17 thereof is raised and lowered in the conventional or usual manner.

In Figures 5 and 6, the block or work 22 is

engaged against the same backing 24 as in the other figures and which is held in place by the same clamp 26. The center punch is the same as in the preceding figures and the same reference numerals have been applied thereto. In this instance, the center punch rests on or is supported by a planer gauge 31 although it may be supported on standard gauge blocks or otherwise. The punch may be used as a scratch gauge in this instance as in the preceding instance and the block 22 may be turned 90 degrees so that intersecting scratches may be effected so that point 15 may be used to prick the same at the point of intersection. In this instance, a hammer or other tool 38 may be used to deal a blow 15 against the outer end of the center gauge, as suggested in dotted lines in Figure 5.

As a result of the invention, the prick mark may be made as accurately as the vernier height gauge or other gauge or support can be set. The work can be set in a lathe with a test indicator to determine the accuracy of the prick mark and the hole can then be bored. Also, the prick mark may be used as a center in drilling in a drill press with a small drill and in many other ways known to tool and die makers.

Various changes may be resorted to provided they fall within the spirit and scope of the invention.

vention as hereinafter defined by the appended claims.

I claim as my invention:

1. In tapper mechanism for a center punch mounted on the slide of a gauge, a tapper, and means on the tapper having an opening whereby it may embrace the slide and contact the punch upon delivery of a blow imparted to the tapper.
2. In tapper mechanism for a center punch mounted on the slide of a gauge, a tapper, a loop thereon having an opening whereby it may embrace the slide and contact the punch upon delivery of a blow imparted to the tapper, said tapper comprising relatively slidable sections, spring means urging separation of the sections and a connection between the sections holding them together and guiding their relative movement.
3. In tapper mechanism for a center punch mounted on the slide of a gauge, a tapper, a loop thereon having an opening whereby it may embrace the slide and contact the punch upon delivery of a blow imparted to the tapper, roller means carried by the loop to directly engage the center punch, a stud extending from the loop, a head telescoped over the stud, and an expansive spring within the stud and head.

JOHN F. MCQUILLAN, SR.
